CHRISTMAS TREE ORNAMENT

Dario Moranduzzo, Via Aretina 161, Florence, Italy

Filed Oct. 22, 1965, Ser. No. 87,770

Term of patent 14 years

(Cl. D29—1)

The sole figure of the drawing is a perspective view of a Christmas tree ornament showing my new design, the side opposite being a mirror image thereof.

I claim:

The ornamental design for a Christmas tree ornament, as shown and described.
